UNITED STATES PATENT OFFICE.

JAMES E. LAPPEN, OF WINONA, MINNESOTA, ASSIGNOR TO UNION FIBRE COMPANY, OF WINONA, MINNESOTA, A CORPORATION OF MINNESOTA.

MACHINE FOR MAKING FIBER INSULATING-SHEETS.

1,139,982.

Specification of Letters Patent.

Patented May 18, 1915.

Application filed May 15, 1913. Serial No. 767,888.

To all whom it may concern:

Be it known that I, JAMES E. LAPPEN, a citizen of the United States, residing at Winona, in the county of Winona and State 5 of Minnesota; have invented certain new and useful Improvements in Machines for Making Fiber Insulating-Sheets, of which the following is a specification.

My invention relates to improvements in 10 machines for making insulating sheets of fiber, having special reference to flax, hemp, or jute fibers, but capable of being used with other suitable fibers.

The objects of the invention are to provide 15 improved means for interlacing and inter-tangling the fibers so as to make the sheets strong and coherent, and for washing the fiber during its progress through the machine and carrying away the impurities 20 therein so as to prevent deterioration of the finished sheet, as well as to simplify the apparatus for making these sheets and make it more efficient.

According to the method now in common 25 use, the fibrous material from which such insulating sheets are made is first treated in a digester with an alkali solution to remove the gummy constituents. It is then delivered in a damp state upon a traveling 30 apron which carries it first through water in a tank, where the fibers are distributed and interlaced in a horizontal plane by manual or mechanical means, and then under a succession of pressure instrumentalities, 35 such as rolls and tampers, to squeeze out the water and complete the felting of the fibers. This method of manufacture, however, does not adequately remove from the fiber the dirt and alkali which remain in it after its 40 treatment in the digester, because the water in the tank is used over and over again and soon becomes full of alkali and dirt from the fiber, so that the fiber remains impregnated with the alkali and other impurities 45 when it leaves the tank. This makes the product harsh, brittle, and discolored. Furthermore, in machines now commonly used there is no positive means for driving the fibers into the mat in a direction trans- 50 verse to the plane thereof.

In order to overcome these defects and to attain the objects mentioned above, I have devised a machine wherein the fibers are not carried through a tank of water, but are

carried on a foraminous apron underneath 55 sprays or jets of water which are delivered upon it from above, and which not only drive the fibers downwardly across the plane of travel of the apron, but also wash the alkali and dirt down through the openings 60 therein. As the apron does not travel through water but only receives the water from above, the alkali when once washed from the fibers is carried off through the openings in the bottom of the apron and 65 will not re-impregnate the fibers. As the fiber mat is rather thick it will somewhat impede the downward passage of the water so that the fiber will be more or less submerged, particularly if the apron is de- 70 pressed between its ends.

More particularly the invention consists in the construction, combination, and arrangement of parts hereinafter described and claimed.

In the accompanying drawings showing the preferred embodiment of my invention, Figure 1 is a top view of the machine with some parts broken away; Fig. 2 is a cross section on line $y-y$ of Fig. 1; Fig. 3 is a 80 longitudinal section through the machine on line $w-w$ of Fig. 1; Fig. 4 is a bottom view of one of the sprayers; Fig. 5 is a plan view of the apron slats; and Fig. 6 is a cross section through the same on line $z-z$ of Fig. 5. 85

In the machine shown in the drawings, I have shown doffer mechanism A of a type well known in the art for delivering the fiber upon the traveling apron B. This apron is an endless conveyer consisting preferably 90 of side sprocket chains 2 and traverse slats 3 formed with a large number of holes 4 to permit the water to pass down through them. The apron passes over an idler roller 5 at the feed end of the machine and a 95 driven roller 6 at the forward or delivery end of the machine. The roller 6 may be driven from the main drive pulley 7 by any suitable mechanism such as the gear 8 upon the shaft of the pulley 7 which meshes with 100 a gear 9 upon the shaft of the roller 6. The roller 6 carries at each end sprocket teeth 10 which engage the sprocket chains 2 of the apron, and thereby drive the apron.

The top reach of the apron travels from 105 the roller 5 over a table 11, where it receives material from the feeding devices. It then passes down over sprockets 12 to the de-

pressed horizontal portion of the skeleton ways 13, and runs along these ways to the roller 6. These ways consists preferably of spaced guide rails supported upon the framework C. They run horizontally from a point near the sprockets 12 at a considerably lower level than the table 11 to a point near the delivery end of the machine, whence they rise upon an incline to the roller 6. The apron is kept depressed upon the horizontal portion of the ways by means of spaced underrunning idler sprockets 14 and 15, journaled in the framework and, like the sprockets 12, engaging the side sprocket chains of the apron, the sprockets 14 being placed near the table 11 in close proximity to the sprockets 12, and the sprockets 15 being placed at the point where the ways begin their upward incline.

The apron runs between side walls 16 which extend well above the ways so as to prevent the water which is delivered upon the fiber from escaping at the sides. To protect the edges of the fiber mat from being torn by the sprockets 14 and 15, I have provided auxiliary side walls or deckles 17 on the inner sides of these sprockets above the apron.

Supported in any suitable manner above the apron at a point between the depressing sprockets 14 and 15 are spraying pipes 19 which extend entirely across the machine. These pipes are connected with a valved supply pipe 20, through which water is forced under pressure, and are closed at their outer ends. The pipes 19 are formed in their underside with a row of holes 21, as shown in Fig. 3, so that, when the valve 22 in the supply pipe is opened, the water will be discharged with more or less force upon the fiber which is being carried along on the apron, and will pass down through the fiber and escape through the joints and holes in the apron. To collect and carry off this dirty water before it falls on the lower reach of the apron I have arranged an inclined pan 23 which extends longitudinally of the machine between the upper and lower reaches of the apron. It is supported upon the framework C and at its lower end leads into a trough 24 having a drain pipe 25.

As the apron is carried up the inclined portion of the ways 18 it passes under vertically reciprocatory tampers 26, which may be driven from any suitable source of power, and between the compression rollers 6 and 27, whereby to compact the intertwined fibers and expel the water therefrom. As these tampers and compression rollers are old in the art and form no part of the present invention no detailed description of them is necessary. After the fiber sheet has been carried through the rollers 6 and 27, it is delivered from the apron to press rolls 28 and 29 which, like the tampers and the

roller 27, may be driven from any suitable source of power. From these press rolls it passes on to a suitable table or conveyer 30.

In use the fiber, which is usually in a somewhat wet and matted condition, is deposited by any convenient means upon the top reach of the apron before it has passed off the table 11. It is then carried down along the depressed horizontal portion of the ways 13 under the jets of water which are delivered from above through the spraying pipes 19. The water drives some of the fibers down into the mat so that they will assume a position transverse to the plane of the apron, and turns others into all sorts of positions, so that the fibers will become intertwined and interlaced. As the mass of fiber is thick the water will not all make its way at once through the fiber and escape through the openings in the apron, but much of it will collect upon and about the fiber and soak and loosen the same. It will be seen that the water cannot escape at the sides of the apron on account of the deckles 17 and side walls 16, nor off the ends of the apron because the ends are raised above the depressed intermediate portion. Thus the apron, instead of running through a tank, will itself constitute a sort of traveling tank, but one to which fresh water is constantly supplied and from which the dirty water is constantly running off through the openings in its bottom, carrying with it the alkali and other impurities washed from the fiber.

After passing along the depressed or tank portion of the apron, the fiber is carried up the inclined portion of the ways, and in its passage up is drained of most of the free water carried along by it. It is then subjected to the action of the tampers and pressure rolls which expel the remaining water and complete the felting of the fibers. By the term "water" as used herein I mean to include any liquid which will act mechanically in substantially the same way as water.

The details of the structure can be modified in various ways, without departing from the principle of the invention, the scope of which is defined in the claims.

I claim as my invention:

1. In a machine for making fiber insulating sheets, the combination with a traveling foraminous apron adapted to carry loose fibrous material, of means arranged above the apron for driving jets of water upon the material carried thereon with sufficient force to deflect and intertwine the fibers.

2. In a machine for making fiber insulating sheets, the combination with fiber feeding and fiber felting instrumentalities, of an endless foraminous conveyer traveling from said feeding instrumentality to a point below the level thereof and then up again to said felting instrumentality, and means ar-

ranged above the apron for delivering jets of water thereon during the depressed portion of its travel.

3. In a machine for making fiber insulating sheets, the combination with fiber feeding and fiber felting instrumentalities, of an endless foraminous conveyer apron adapted to carry fibrous stock from said fiber feeding instrumentality to said fiber felting instrumentality, means for depressing said apron intermediately of said instrumentalities, and means arranged above the apron for driving jets of water upon the depressed portion of the apron with sufficient force to deflect and intertwine the fibers carried along thereby.

4. In a machine for making fiber insulating sheets, the combination with fiber feed-

ing and fiber felting instrumentalities, of an endless foraminous conveyer apron traveling from said feeding instrumentality to said felting instrumentality, means for depressing said apron intermediately of said instrumentalities, a sprayer arranged above the depressed portion of the apron and adapted to discharge water thereon, and retaining walls on both sides of the apron for preventing the water from escaping at the sides.

In testimony whereof I affix my signature 30 in presence of two witnesses.

JAMES E. LAPPEN.
